UNITED STATES PATENT OFFICE.

AUGUST E. HELMAN, OF CLEVELAND, OHIO, ASSIGNOR TO THE W. S. TYLER COMPANY, OF CLEVELAND, OHIO, A CORPORATION OF OHIO.

METHOD OF MAKING WOVEN-WIRE SCREENS.

Original application filed June 9, 1927, Serial No. 197,643. Divided and this application filed June 20, 1928. Serial No. 286,999.

The present invention, relating as indicated to a woven wire screen, is more particularly directed to an improved method of making a woven wire screen to avoid the necessity for rolling or flattening the screen after weaving, for the purpose of bringing into substantially the general plane of the screen the knuckles or knees of the wires. Ordinarily woven wire screen is frequently 10 hammered or rolled to render the surface level and to flatten out the so-called knuckles of the wires, and in this process the wires, which are ordinarily preliminarily crimped or bent, are opened up slightly at the knees, 15 thus causing a release of the engagement which otherwise would be effected by the transverse wires upon the longitudinal wires, with the result that the rolling or flattening process, while benefitting the 20 screen in one respect is a serious detriment in another and produces a screen which is loose, sleazy, and very much more subject to movement of the wires out of their original position with the resultant inaccuracy of the 25 grading of materials. In many cases the rolling of the screen distorts the mesh so much that it cannot be used at all and in almost every case some distortion is produced by rolling.

30 The present invention is directed to an improved method of making a woven wire screen, and particularly to an improved method of preliminarily treating one or both series of wires to secure the desired 35 results without losing any of the benefits of the employment of preliminarily crimped transverse wires.

To the accomplishment of the foregoing and related ends, said invention, then, consists of the means hereinafter fully described and particularly pointed out in the claims; the annexed drawing and the following description setting forth in detail one method of carrying out my invention, such disclosed 45 procedure constituting, however, but one of the various applications of the principle of my invention.

In said annexed drawings:—

Fig. 1 is a transverse sectional view showing a pair of crimping rolls with wires passed therebetween; Fig. 2 is an enlarged sectional view showing the action of the rolls on the wire; Fig. 3 is an enlarged view of the wire after the crimping treatment;

Fig. 4 is a transverse sectional view of a 55 screen woven with transverse wires treated by my improved method; Fig. 5 is a plan view of my improved screen; Fig. 6 is an end view of the same; and Fig. 7 is a transverse section of the screen upon an enlarged 60 scale.

Referring now to Fig. 1, there are shown two co-operative rolls 1 and 2, which are provided with a series of teeth or corrugations 3 and 4, respectively. Between these 65 two rolls is passed a wire 5 which, as it is engaged between the teeth, is bent into corrugated portions 6, shown at the left of Fig. 1. The rolls 1 and 2 are so spaced and the corrugating elements or ribs 3 and 4 are so 70 proportioned in depth and in spacing from each other that as the wire is engaged between the rolls the apex 7 of each rib or tooth forces the wire against the recess 8 in the other roll corresponding in position 75 to the tooth 7 and slightly flattens the crest 9 of the crimped portion of the wire and also the recessed surface 10 of the same portion, since the spacing between the apex of the tooth and the corresponding recess of 80 the other roll is less than the normal thickness of the wire 5. The teeth of the rolls are spaced apart sufficiently so that the wire when crimped is not forced completely into contact around the sides of the ribs or teeth, 85 but is spaced slightly from these sides, as indicated in Fig. 2, except at the crests of the corrugations, with the result that the metal intermediate the crests of the successive corrugations is not engaged by the teeth 90 and is not worked or hardened during this action. The crests of the corrugations which form the so-called knuckles of the woven screen are, however, worked and hardened during the bending and flattening operation, 95 producing a much increased rigidity and strength at the intersections, that is, the interengaging points of the transverse and longitudinal wires of the final screen. In some cases only the transverse or the longitudinal wires are preliminarily crimped, 100 and a screen formed of such wires is very much superior to one made in the former way and then rolled.

The form of the preliminarily crimped wire is shown in Fig. 3 and the finished screen in Fig. 4. In the latter view the longitudinal wires 11 are shown received

within the angular recesses or knuckles 12 of the transverse wires 5, and these longitudinal wires are there being held without any loosening of the engagement. Frequently 5 the wires are loosened when the woven screen is rolled by the old method to bring the knuckles into the general plane of the screen, as has already been explained. In this view there are also shown the flattened crests 9 of 10 the corrugations in the transverse wires.

My improved screen, or one made by my improved method hereinbefore described, is equally level and flat as screens made by previous methods, is very much more rigid and less subject to variation in the spacing between longitudinal wires, and is stronger in the wires which have been crimped because of the temper given to the knuckle portions 15 of the corrugations by the action of the crimping rolls. A further important advantage of the present screen lies in the fact that a better screen of a materially longer life may be produced at a lower cost than that of the former screens.

25 This application is a division of my application Ser. No. 197,643, filed June 9, 1927.

Other modes of applying the principle of my invention may be employed instead of the one explained, change being made as regards 30 the method herein disclosed, provided the step or steps stated by any of the following claims or the equivalent of such stated step or steps be employed.

I therefore particularly point out and distinctly claim as my invention:—

1. In a method of making a woven wire screen, the steps which consist in preliminarily bending one series of wires into crimped condition with an exact and predetermined spacing between the crimps therein, simultaneously flattening the crest of 40 each of such crimps to harden and increase

the rigidity of the wires at such points, and then weaving said wires into a screen by arranging them in parallelism and positioning a second set of wires at right angles to the first set and engaged in locked relation in the flattened portions of said first-named wires.

2. In a method of making a woven wire screen, the steps which consist in preliminarily bending one series of wires into a crimped condition with an exact and predetermined spacing between the crimps therein, simultaneously flattening the crest of 45 each of such crimps to harden and increase the rigidity of the wires at such points, bending the second series of wires also into a crimped condition with an exact and predetermined spacing between the crimps 50 therein, also simultaneously flattening the crests of the crimped portions of said second series of wires, and then weaving said wires into a screen by arranging the first set in parallelism with the respective crimps in 55 transverse alignment and positioning said second series of wires at right angles to the first, while causing the flattened crimped portions of both series of wires to be engaged in locked relation with each other.

3. In a method of making a woven wire screen, the steps which consist in preliminarily crimping the transverse wires to the contour required in a woven screen, simultaneously flattening the upper and lower surfaces at the crest of each of such crimps to harden and increase the rigidity of the wires at such points, and then weaving said preliminarily crimped transverse wires through 70 parallel longitudinal wires to produce a 75 woven wire screen.

Signed by me, this 16th day of June, 1928.

AUGUST E. HELMAN.
